FOUNTAIN BRUSH

Irving W. Jorgensen, Owosso, Mich.

Application August 25, 1958, Serial No. 52,357

Term of patent 14 years

(Cl. D9—2)

Figure 1 is a plan view of a fountain brush embodying my design;

Fig. 2 is a side elevational view thereof;

Fig. 3 is an end elevational view taken from the left-hand end of Fig. 2;

Fig. 4 is an end elevational view taken from the right-hand end of Fig. 2; and

Fig. 5 is a perspective view with a portion of the brush teeth omitted for convenience of illustration only.

I claim:

The ornamental design for a fountain brush, as shown.
